UNITED STATES PATENT OFFICE

2,619,444

METHOD OF PRODUCING STRUCTURAL ELEMENTS FROM WEB MATERIAL

John Alpe Grantham, London, England, assignor to Dufay Limited, London, England, a British company

Application February 27, 1948, Serial No. 11,573
In Great Britain February 6, 1947

Section 1, Public Law 690, August 8, 1946
Patent expires February 6, 1967

6 Claims. (Cl. 154—117)

1

The present invention comprises improvements in or relating to the production of structural elements from web material and afford both a method and apparatus more suitable for producing such elements in quantity than methods and apparatus hitherto proposed.

The structural elements, the production of which is contemplated by the invention, are similar in form to those the production of which is described in the specification of United States Patent No. 2,428,979. Such elements comprise strips or sheets of paper or like material the adjacent surfaces of which have been caused to adhere in lines or rows in staggered relationship for successive pairs of adjacent surfaces so that a lattice or honeycomb structure is produced when the strips or sheets are spaced from one another as when a pile or stack of such strips or sheets is opened out by moving the outermost strips or sheets apart.

The present invention provides a method of producing structural elements from sheet material wherein a continuous web of such material is folded on itself in succession from opposite ends of successive layers of a pile or stack of folded web material so produced and wherein continuous or interrupted lines of adhesive are applied to the web to be in alternate staggered relationship between successive layers of the folded material. The adhering layers so formed are conveniently cut as required and opened out to form the lattice or honeycomb structure which may be converted into a substantially rigid form and/or finally enclosed as a spacing element between facing material.

Conveniently the lines of adhesive are applied to the web prior to the folding of the latter and conveniently also are applied to the two surfaces of the web respectively in staggered relationship.

Two specific embodiments of the invention will be described by way of example with reference to the accompanying drawings in which:

Figure 1 is a side view of apparatus constituting one specific embodiment of the invention.

Figure 2 is a side view of an alternative arrangement of the feeding and gluing rollers for the web in such apparatus.

Figure 3 is a fragmental view partly in section of feed rollers for the web.

Figure 4 is a similar fragmental view of the gluing rollers.

Figure 5 is a similar view of further feed rollers.

Figures 6 and 7 are similar views of alternative forms of gluing rollers.

2

Figure 8 is a front elevation of a folding arm. Figure 9 is a section, looking in the direction of the arrows on the line 9—9 of Figure 8.

Figure 10 is an enlarged side elevation of the free end of a folding arm.

Figure 11 is a side view of apparatus constituting the second specific embodiment of the invention with an optional portion thereof shown in chain lines.

Figure 12 is a central vertical section through reciprocating parts of the apparatus of Figure 11 showing their application to the web material, and

Figure 13 is a side view on an enlarged scale of the folding carriage and platen shown in Figure 11.

Like reference numerals are employed to denote like parts in the various figures of the drawings.

As shown in Figure 1 illustrating the first embodiment, the web material 10 in convenient width in roll form is mounted on a suitable carrying bracket 11 and feeds to an overhead flanged guide roller 12 from which the web feeds vertically downwards through feed or pinch rollers 13, gluing rollers 14, and additional feed rollers 15. These rollers are connected together, as shown, in sets on opposite sides of the web material 10 and are rotated by means of a chain drive to wheels 16 adjacent pairs of which on opposite sides of the web are arranged to turn inwardly by intermediate gearing not shown. The chain wheels 16 are in turn driven from a lay shaft 17 with final drive from a chain wheel 18 mounted on the main driving axle 19 operated by the motor 20. The gluing rollers 14 are fed with glue from pick up rollers 21 partially immersed in glue in the troughs 22.

The rollers referred to above are constructed as shown in Figures 3 to 5, the pinch rollers 13 having an outer surface of suitable web driving material. Ribs 23 are formed on the gluing rollers 14 either integrally, or in the manner shown in Figure 4 by building up alternate discs 23 and spacing pieces 24 on the supporting shaft 25. The peripheries of the discs 23 may be formed with a slightly concave cross-section or otherwise to pick up and distribute the glue on the web material in the most convenient manner. Guiding flanges 26 are supplied to both ends of one gluing roller, or to alternate ends of each pair of rolls as indicated in the drawings. In the same manner guiding discs 26 are also fitted to the feed rollers 13 and preferably also, though not shown in the drawings, to feed rollers 15 which are formed with recesses 27 either

formed integrally with the rollers or, as shown in the drawings, by forming the rollers 15 from a number of roller portions 29 on the supporting shafts 28 with spacing discs 30 of less diameter than the rollers. The discs 30 and recesses 27 are arranged to coincide with the glue lines applied by the rollers 14. The web material 10 is driven at a continuous linear speed and will form itself into a loop as shown in chain lines in the position 31 of Figure 1. The formation of successive layers of the material takes place on a flat bed or platen 32 which is conveniently wood faced or otherwise surfaced. The platen 32 is capable of vertical movement in the guides 33. Arms 34 pivoted adjacent the ends of platen 32 at the top of guides 33 are driven through an angle of approximately 120° by means of the linkage 35, 36, connected to projections 37 formed integrally with the pivoted arms 34 which act as pressure platens, the link 36 being connected to a flywheel or crank disc 38 on the main driving shaft 19 and the two projections 37 being connected together by the connecting link 35. Power for the whole machine from the motor 20 is derived from a belt or other suitable transmission.

For small production units, however, the arms or pressure platens 34 may alternatively be oscillated by hand through any suitable lever mechanism connected to the link 36.

For power operation, and particularly in the formation of a multiple series of layered blocks of web material, the platen 32 is caused to descend automatically at a rate such that the working level of the layered block in formation is always at the same horizontal level as the pressure platens 34 when in a final position as applied to the web, this being accomplished by means described hereinafter. With the web material 10 in the free loop 31, the left hand platen arm 34 pivots in an arc bringing with it the material 10 to fold the latter down on the main body of the layered block if partially formed. The glued tracks previously applied cause the web (e. g. of paper) to adhere in a folded position secured at intervals to the next lower folded layer by the lines of glue. The platen arms 34 are furnished with ribs 39 which as seen in Figures 8 and 9 are spaced to allow the glued tracks formed on the side of the web material contacted by the platen arms to lie between the ribs without contact with the platen arms.

It should be noted with reference to Figure 4 that the glued tracks are arranged to lie in staggered relation on opposite sides of the web material and grooves in the two feed rolls 15 and ribs in the two pressure platen arms are accordingly also in similar staggered relationship.

After a loop has been taken up by the left hand platen arm 34 a further loop is formed during the short rest period during which the platen arm is in contact with the block, and this further loop is again taken up, this time by the right hand pressure platen arm 34 which moves towards the block while the left hand pressure platen is being retracted.

During the build up of sheets formed in this manner, the platen 32 descends in synchronism, as previously stated, by means of the nut 40 running in a bearing 41 and operating on the platen screw 42. The nut 40 is rotated by the bevel gears 43 and 44 which are in turn driven intermittently by means of the ratchet 45 and gears

46, the ratchet 45 in turn being operated by the eccentric 47 mounted on the main shaft 19.

On completion of a layered block, or series of blocks, the dog-clutches 48 are operated by means of the link 49, by hand or otherwise as desired, to disconnect the main power drive of the nut 40 and bringing into action the motor 59 operating through a suitable reduction gear 51 and gear 44 to reverse the direction of the nut 40 and raise the whole platen 32. Means are provided but not shown in the drawings for temporarily releasing one of the pressure platen arms 34 in order to allow the completed layered block or series of blocks to be brought up to the top of the guides 33 for removal, the procedure being then to place the completed blocks under pressure during setting of the glue after which the folded edges are removed by means of a guillotine. Subsequent treatment of the layered block may then be effected as described in the specification of U. S. patent application No. 718,720, now abandoned.

Horns 52 seen in Figures 8 and 10 are fitted to the platen arms 34 in order to engage and guide the web material 10 during engagement herewith, rollers 53 being fitted at the tips of the platen arms to engage the web to prevent wear and to reduce friction. Holes 54 are also drilled through the material of the pressure platen arms 34 at suitable spaced positions in order to obviate any suction effect when the platen is released from engagement with the layered block on commencement of its upward stroke.

The arrangement of feed and gluing rollers may alternatively be as shown in Figures 2, 6 and 7 in which it will be seen that the gluing process is carried out in two stages, the web material 10 being passed from the pinch rollers 13 to the first stage in which the gluing roller 14 of the form previously described, is supported or opposed (as shown in Figure 6) by a plain roller 55 (similar to the pinch or drive rollers 13) to apply glue to the right hand side of the web. This treatment is followed by passage through a further pair of rollers of which one is a gluing roller 14 as previously described, for applying glue to the left hand side of the web 10, and the other a supporting or opposing pressure roller 56 of the form shown in Figure 7 and having recesses formed to allow for the passage of the portion of the web already glued. The roller 56 is in fact similar to the rollers 15, and the gluing rollers applied to opposite sides of the web are again arranged to apply the glue in lines or rows (e. g. rows of dots) in staggered relationship.

Any desired adhesive may be employed in place of the glue to which reference is made and the paper or like web material may, if desired, be impregnated with a synthetic resinous condensable or polymerisable material at any convenient stage.

The second specific embodiment of the invention shown in the drawings to which reference has been made is similar in many respects to the apparatus described above but employs a reciprocating roller carriage in place of the pressure platens 34.

Thus in the second embodiment of the invention as shown in the drawings the web material 10 arranged in roll form passes over a guide roller 12, feed rollers 13, gluing rollers 14 and final feed rollers 15 to form a loop 31, a chain drive of the rollers being effected from the lay shaft 17 and from the main driving shaft 19 and

motor 20. Adjoining a main pressure bed or suspending platen 32 on which the web material is received and laterally on each side of the bed are arranged guide rails 60 supporting a carriage 61 running on flanged wheels 62 and a roller 63. The flanged wheel and roller may with advantage be arranged in the manner shown, with the two flanged wheels 62 running on the one guide rail and one un-flanged roller running on the second guide rail, to give three point suspension and accurate linear guiding of the carriage 61, the guiding being effected from one guide rail only.

The carriage 61 is intended to reciprocate on its support and carries two pressure rollers 64 formed with ribs with the ribs on the two opposing rollers 64 spaced in staggered relationship so that the glue lines on opposite sides of the web material 10 may pass between the ribs without contacting the rollers 64 as they reciprocate over folded layers of web material fed between the rollers 64 and applied to the bed or platen 32, the glue lines applied by the rollers 14 being in staggered relationship on opposite sides of the web. The rollers 64 are carried by connecting links 65 at each end of the carriage 61 to allow a vertical movement of the rollers to take place about the hinge pins 66 of the links 65. Additional pressure on the rollers 64 may be arranged by means of weights 67 but tension or compression springs may alternatively be arranged for this purpose as may be convenient. The carriage 61 is connected to the main crank pin on the fly wheel or crank disc 38 on the shaft 19 by means of a connecting rod 68 whereby reciprocation of the carriage 61 in a horizontal plane is effected. The rod 68 is pivotally connected at 69 to a projection on the carriage 61. The traverse of the latter is arranged slightly to overlap the ends of the bed 32 and retaining claws may be provided to ensure folding of the web at the desired positions at the said ends.

Downward feed of the built up layered material applied to the bed 32 by such reciprocation is arranged for as in the apparatus previously described through a screw 32 and rotatable collar 40 operated through bevel gears 43 and 46 and ratchet 45 driven by eccentric 47, while motor 50 and clutches 48 again enable the bed to be raised with a number of layers of web material 50 thereon.

The whole apparatus which has been described may, if desired, be arranged in duplicate with a common crank shaft to secure operation also of the second and right-hand apparatus indicated in chain lines at 70 and 71. Such a right-hand carriage is arranged to be driven by means of an additional crank throw not shown in detail in the drawings, with the two crank pins for the two duplicate machines spaced 180° apart. In this way the masses of the two reciprocating carriages are mutually balanced with the exception of a

negligible primary couple due to the separation of the crank throws.

Means are also provided, though not shown in the drawings, for running the carriage 61 clear of the bed 32 to allow a finished stack of layered material to be raised up on completion above the level of the pressure pads in order to facilitate removal of the finished stack which may be subsequently treated in a like manner to that referred to above.

I claim:

1. Method of producing structural elements from sheet material comprising the steps of applying parallel lines of adhesive to the respective sides of a web of material, the lines of adhesive on one side of the web being staggered relatively to the lines of adhesive on the other side of the web, feeding the web continuously in a downward direction, successive portions of the web being momentarily suspended in generally vertical position, deflecting successive portions of the web alternately to one side or the other of said generally vertical position, and folding said successive portions downwardly about their respective lower edges to form successive horizontal layers of a pile, the feeding and folding steps being carried out at such relative speeds that the suspended portion of the web is always of sufficient length to permit its being folded without appreciable drag thereon.

2. The method of claim 1, the suspended successive portions of the web hanging as loops disposed alternately to one side and the other of the point of suspension.

3. The method of claim 1, including continuously lowering said pile at a speed corresponding to the rate at which its height is increased by the depositing of additional layers thereon.

4. The method of claim 1, the applications of adhesive to the respective sides of the web being performed simultaneously.

5. The method of claim 1, the applications of adhesive to the respective sides of the web being performed successively.

6. The method of claim 1, including cutting and opening out the pile to form a lattice structure.

JOHN ALPE GRANTHAM.
